(57) **CLAIM**

We claim the ornamental design for a two-pronged latch for a downhole tool, as shown and described.

DESCRIPTION

FIG. 1 is a perspective view of a two-pronged latch for a downhole tool showing our new design.

FIG. 2 is a perspective view of the prongs of the two-pronged latch of FIG. 1.

FIG. 3 is a front plan view of the prongs of the two-pronged latch of FIG. 1.

FIG. 4 is a rear plan view thereof.

FIG. 5 is a top plan view thereof.

FIG. 6 is a bottom plan view thereof.

FIG. 7 is a right side elevation view thereof.

FIG. 8 is a left side elevation view thereof.

FIG. 9 is a front plan view of one of the prongs of the two-pronged latch of FIG. 1.

FIG. 10 is a perspective view of the two-pronged latch for a downhole tool, wherein the two prongs have pivoted outwardly about respective pin-holes.

FIG. 11 is a front plan view of the two-pronged latch of FIG. 9.

FIG. 12 is a rear plan view thereof.

FIG. 13 is a top plan view thereof.

FIG. 14 is a bottom plan view thereof.

FIG. 15 is a right side elevation view thereof; and,

FIG. 16 is a left side elevation view thereof.

The structural features shown in broken lines have been shown for the purpose of illustrating environment, and form no part of the claimed design.
